(57) **CLAIM**

The ornamental design for a sole for footwear, as shown and described.

DESCRIPTION

FIG. 1 is a bottom plan view of a sole for footwear showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom rear, right perspective view of thereof;

FIG. 8 is a bottom front, left perspective view thereof; and,

FIG. 9 is a top front, right perspective view thereof.

The broken lines of uneven length illustrate the boundary of the claimed design. The boundary lines and the lightened portions within the boundary form no part of the claimed design.

1 Claim, 9 Drawing Sheets
